DOCUMENT PROTECTOR

Application filed June 28, 1929. Serial No. 374,573.

The invention relates generally to a document protector and, more specifically, to a device for preventing the alteration of written or printed documents without noticeably disfiguring said document.

It is an object of the invention to provide a novel device of this character which is simple in construction, easy to operate, and which alters the body of the document, after it has been completed, in a manner which is ordinarily unnoticeable to a casual observer but which becomes strikingly apparent if an attempt is made to alter, erase, insert or in any way change the original writing.

Another object of the invention resides in the provision of a document protector embodying a means for perforating the portions of the document to be protected with countless numbers of almost invisible punctures dispersed throughout the entire treated surface.

Other objects and advantages will become apparent in the following description and from the accompanying drawings, in which:

Fig. 1 is a central vertical section of a device embodying the invention and is taken substantially along the lines 1—1 of Fig. 2.

Fig. 2 is a plan view of the device, the cover being removed to disclose the general arrangement.

Fig. 3 is a transverse section taken on the lines 3—3 of Fig. 1.

Fig. 4 illustrates a document before and after it has been subjected to the action of the device.

Fig. 5 is a diagram of the electric circuits.

In general, the organization of the device comprises a housing or casing which is constructed to provide a passageway or channel through which the document to be treated may be passed. On opposite sides of the passageway elongated electrical conductors are mounted in opposed relation to each other, said conductors being connected to a source of high potential current arranged to produce a series of sparks between the conductors which are capable of perforating an interposed document. In addition, the conductors are arranged for rapid relative movement so that the sparks will be successively

discharged at different points on the conductors thereby producing what may be termed a series of sparks traveling along the conductors. In consequence, the relative movement of the conductors being rapid, the series of sparks traverses and perforates the entire surface exposed to the action thereof.

More particularly describing the invention, the drawings illustrate a preferred form of device by which the objects of the invention may be attained. Referring thereto, 10 indicates generally the bottom section, and 10^a the top section, of a casing which encloses and supports the operating parts of the device. The bottom section 10 has a base 11 formed preferably of a dielectric material, and side and end walls 12 and 13, respectively. The side and end walls may be formed of a single piece of material properly shaped and secured to the base.

Mounted within the bottom section, and at opposite ends thereof, are supporting blocks 14, 15 also of dielectric material. One of the blocks, in this instance the block 14 (Fig. 1), is of less height than the adjacent end wall and is substantially L-shaped so that when assembled the short leg 16 of the block extends inwardly of the casing. A pair of upright pieces 17 (Fig. 3) are supported on the upper surface of the leg 16 adjacent the inner edge thereof, which pieces are of such width that there is a gap 17^a of substantial size therebetween.

The upper face of the bottom section is arranged to be substantially closed by means which provides a surface over which the document to be treated may pass. For this purpose a pair of elongated strips 18 (Fig. 3) rest, at one end, upon the upper surfaces of the upright pieces 17, and at the other end within recesses formed in the end block 15. The strips 18 extend longitudinally of the bottom section and the upper surfaces of the strips are substantially flush with the upper edges of the side walls of the casing. In width the strips are somewhat wider than the width of the upright pieces 17, but their adjacent edges are spaced apart to provide a gap 18^a therebetween which extends longi-

tudinally and substantially centrally of the casing.

The top section is preferably in the form of a dish-shaped member (see Figs. 1 and 3) having side and end walls thereon which register with the side and end walls of the bottom section when the open faces of the two sections are brought together. Within the top section and adjacent the ends thereof are crossbars 19, 20 of dielectric material positioned to engage the upper surfaces of the strips 18, above the upright pieces 17 and the end block 15, respectively. Suitable means, such as the screws 21, are employed to secure the two sections together and for convenience these screws may also serve to hold the strips 18 at each end and the upright pieces 17 at the one end (see Fig. 3) in assembled relation. The side edges of the top section intermediate the cross-bars 19, 20 are recessed or cut away, as at 22, to provide a transverse document passage or slot (Fig. 1) through the casing across the upper surfaces of the strips 18 and the intermediate gap 18^a therebetween.

Referring to the construction of the electrical conductors, it is contemplated that the desired end may be effected in various other ways but I have found that highly satisfactory results may be obtained by placing a rotating conductor adjacent but spaced from a stationary conductor. By forming the rotating conductor in the shape of a spiral, the adjacent edges of the two conductors may be said to have an angular rather than a parallel relationship, in consequence whereof movement of the rotary conductor causes the point of closest proximity of the edges, which, of course, is the point at which a spark will jump to move rapidly and recurringly the length of the stationary conductor.

The particular construction and arrangement of the conductors may be seen in Figs. 1, 2, and 3. A narrow, elongated strip 23, of some metal which is a good conductor of electricity, is twisted into a spiral form. Preferably, the strip is twisted through 360° or one complete turn, the purpose of which will later become apparent. A bearing pin 24 (Fig. 1) is secured on one end of the strip 23 in axial alinement therewith, and a bushing 25 is mounted in the end block 15 to receive said pin. The bushing is centrally located with respect to the gap 18^a between the two strips 18, and is so positioned adjacent the upper edge of the end block 15 that the periphery of the cylindrical area, described in the rotation of the spiral conductor, is substantially tangential to the upper plane surfaces of the strips 18.

The spiral conductor 23 is driven by an electric motor which, while shown herein as being mounted outside of the casing by means of brackets 27 secured to the casing, may of

course be otherwise arranged. When the motor is so mounted the armature shaft 28 thereof extends into the casing in substantial alinement with the oppositely disposed bushing 25. The spiral conductor 23 extends longitudinally of the casing to position the other end in the gap 17^a intermediate the upright pieces 17 and an insulating member 29, also extending axially of the spiral conductor, is rigidly secured thereto. The free end of the insulating member 29 is recessed to receive and be secured to the end of the motor shaft 28, forming a driving connection between the motor and the spiral conductor.

The top portion 10^a of the casing carries the stationary conductor, which in the present instance comprises two separate conductors arranged to cooperate with the rotating conductor to increase the number of spark discharges. Thus, midway between the two cross insulating bars 19, 20 a third insulated cross-bar 30 is secured which supports one end of a pair of straight conductors 31, 32 extending to the other cross-bars 19, 20 respectively. These conductors are mounted in end to end alinement but are separated and insulated from each other by the median cross bar 30. With respect to the other parts of the device, the exposed edges of the straight conductors are substantially in the plane of the upper side of the slot through the casing, and the conductors lie immediately above and parallel with the axis of the spiral conductor 23. In consequence of this construction, in every position of rotation of the spiral conductor, there will be a portion of an edge of the spiral conductor immediately adjacent each of the stationary conductors.

It may be seen in Figs. 1 and 3 that the lower portion 10 of the casing is of sufficient width and depth to accommodate an induction or spark coil 33 of any well known type. A condenser 34 may also be contained within the casing, if desired, and, where used, is preferably interposed in the circuit leading to the primary coil of the spark coil. The secondary or high-tension circuit of the spark coil includes the rotating and the stationary conductors, the space between said conductors forming a spark gap in the secondary circuit. In the present instance the connections are such that there are virtually two spark gaps, thereby doubling the number of sparks perforating the document. To this end, one of the secondary terminals is connected to the stationary conductor 31 and the other secondary terminal to the other stationary conductor 32 by suitable leads 35, 36 (Fig. 5). Consequently, since the rotating conductor may be said to be common to both stationary conductors, an electric current traversing the secondary circuit passes from one stationary conductor across the separating gap to the rotating conductor, back

across the gap to the other stationary conductor to return to the other secondary terminal. The discharges, therefore, occur at two points, which points, when the rotating conductor is in motion, move simultaneously from end to end along the stationary conductors. Hence, if a document is passed through the slot in the casing, as shown in broken outline at 37 (Fig. 2), substantially the entire document will be perforated by the discharges passing between the conductors. A further advantageous feature of the spiral shaped conductor is that of safety since the rapid rotation of the spiral produces a fanning effect which absolutely eliminates any possibility of the document becoming ignited from the discharges.

Preferably a combined circuit-control means is provided for the motor and the spark-coil, which means requires a positive initial movement by the operator to start and continue operation of the device and is self-releasing or disconnecting to prevent accidental or unintentional operation thereof when not in use. For this purpose, a rod or shaft 38 extends through the casing and bears in the cross-bars 19, 20 and 30. The outer end of the rod is bent to form a crank 39 for rotating the shaft. The inner end of the shaft 38 extends into the small compartment defined by the walls of the casing and the cross bar 19, uprights 17, and the leg 16 of the L-shaped end block. An insulating bushing 40 is snugly but rotatably mounted on this end of the shaft and in turn carries a metallic sleeve 41 (see Fig. 3) which has two switch fingers 42, 43 extending radially therefrom. Preferably the sleeve 41 and the fingers 42, 43 are integrally formed of a somewhat resilient metal. Contact points 44, 45 (Fig. 2) are supported by an insulating bracket 46 mounted on the upper surface of the leg 16 in position to be engaged by the fingers 42, 43 respectively. The fingers, however, (see Fig. 3) extend from the sleeve 41 in different radial planes, so that when the shaft 38 is rotated to move the fingers against the contact points, such engagement is perfected against the resiliency of the spring fingers.

The motor 26 and the primary coil of the spark coil are connected in parallel, and the contact points 44, 45 are interposed in one of the leads 47 to said parallel circuits. Hence, when a positive actuating force is applied to the crank 39 to close the switch, a circuit is established through the contact points 44, 45, switch fingers 42, 43 and sleeve 41. As soon, however, as the crank 39 is released, the resiliency of the switch fingers moves at least one of the fingers away from its corresponding contact point to break the circuit and stop the device.

Inasmuch as the shaft 38 is capable of further rotation after contact has been es-

tablished, the shaft may be employed to feed the document through the passageway by providing one or more cylindrical rollers 38^a, of a resilient material such as rubber, firmly mounted at intervals on the shaft 38, and of such diameter as to engage the surface of a document passing over the surface of the underlying strips 18. Continued rotation of the shaft 38, then, will feed the document through the device, the bushing 40 meanwhile slipping on the shaft without interruption of the established circuit until the shaft 38 is released.

In Fig. 4 I have shown on a somewhat emphasized scale a comparison between a treated, unaltered portion of a check, indicated at A, and a portion B on which an alteration has been attempted. The unaltered portion A presents, to an ordinary observer, the normal appearance of a check. However, if the check is scrutinized closely, or is held to the light, countless numbers of very fine perforations may be seen, and under a magnifying glass it may be seen that the paper at the margin of each hole is charred. If an erasure is attempted the charred margins break away to enlarge the size of each perforation and make them plainly noticeable, even to a casual observer. Where the alteration attempted consists merely in writing additional words or characters, or in writing over a blank where a previous writing has been removed by chemicals, the ink fills each orifice and a very noticeable blurred mark, as shown in B, results. Or the pen-point may catch in any of the holes to produce the same effect. Obviously, if the attempt to add written words is made over an erasure, the evidence of alteration is intensified.

It will be apparent from the foregoing description that a device has been produced which is capable of rapidly treating a written instrument so that any attempted alteration thereof must fail, which device is simple in construction and operation and may be manufactured for sale at a low cost.

I claim as my invention:

1. A document protector comprising, in combination, a casing having a passageway extending transversely therethrough, means within said casing providing a plane surface flush with the lower edge of said passageway, said means having a longitudinally extending gap therein interrupting said surface, a pair of elongated stationary conductors in said casing mounted in spaced relation to said plane surface above said gap therein and aligned in end to end relation, means for insulating said conductors from each other, a rotating conductor mounted in said casing with the upper periphery of rotation lying substantially flush with said plane surface, said rotating conductor being spiral in form and arranged so that a point on said conductor is at all times adjacent to some one

point on each of said stationary conductors, an electric motor for driving said rotating conductor, an induction coil mounted in said casing, electrical connections extending between each end of the secondary circuit of said induction coil and one of the stationary conductors, other leads connecting the motor and the primary circuit of said induction coil in parallel to a source of current, and a 10 control switch interposed in said last mentioned leads.

2. A document protector comprising, in combination, a casing having a passageway extending transversely therethrough, a spirally formed conductor rotatably mounted within said casing adjacent one side of said passageway, a stationary conductor parallel to said spiral conductor adjacent the opposite side of said passageway, and means for 15 effecting electric spark discharges from one conductor to the other during the rotation of said spiral conductor.

3. A document protector comprising, in combination, a support, a conductor in the 20 form of a spiral member rotatably mounted on said support, a second conductor rigid with said support and mounted in parallelism with the axis of rotation of said spiral conductor, said two conductors being spaced 25 apart a short distance to constitute a spark gap, and an electrical circuit including said two conductors for effecting electric discharges across said spark gap to perforate an interposed document.

35 4. A document protector comprising, in combination, a support, a conductor in the form of a spiral member rotatably mounted on said support, means for rotating said spiral conductor, a second conductor rigid with 40 said support and mounted in parallelism with the axis of rotation of said spiral conductor, said two conductors being spaced apart a short distance to constitute a spark gap, an electrical circuit including said two 45 conductors for effecting electric discharges across said spark gap to perforate an interposed document, and means for feeding a document between said conductors.

5. A document protector comprising, in 50 combination, a support, a conductor in the form of a spiral strip rotatably mounted on said support, a straight conductor rigidly mounted on said support adjacent but spaced from said spiral conductor and in parallelism 55 with the axis thereof, an electrical circuit including said two conductors and arranged to effect the discharge of a series of sparks across the intervening gap between the straight conductor and the most adjacent portion of the spiral conductor, and means for 60 rotating said spiral conductor so that said most adjacent portion thereof travels from end to end of the straight conductor.

6. A document protector comprising, in 65 combination, a support, a rotary conductor

mounted on said support, a pair of elongated conductors mounted in end to end alignment adjacent said rotary conductor and parallel to the axis thereof, said rotary conductor being in the form of a spiral having one portion thereof adjacent a portion of each of 70 said elongated conductors to constitute two spaced spark gaps, an electrical circuit including said two stationary conductors and said rotary conductor and arranged to effect the discharge of a series of sparks across both of said spark gaps, and means for driving said rotary conductor to produce a shifting movement of the spark gaps from end to end of the elongated conductors. 75

7. A document protector comprising, in combination, a spirally formed conductor mounted for rotation, a stationary conductor mounted in such spaced relation to said spiral conductor as to provide a spark gap therebetween, an electrical circuit connected to effect a discharge across said spark gap, and feeding means for passing a document through said spark gap between said conductors. 85

8. A document protector comprising, in combination, a supporting surface having a longitudinally extending gap therein, an elongated member of current-conducting material mounted to extend parallel to said gap and in spaced relation at one side of said surface, a second elongated member mounted for rotating movement in said gap and including a peripheral portion of current conducting material in the form of a spiral, 95 means for rotating said last mentioned elongated member, means for effecting electric discharges between said two elongated members, and feeding means for passing a document across said surface between said two 100 members. 105

9. A document protector comprising, in combination, a supporting surface having a longitudinally extending gap therein, an elongated member of current-conducting material mounted to extend parallel to said gap and in spaced relation at one side of said surface, a second elongated member mounted for rotating movement in said gap and including an elongated peripheral portion of current-conducting material in the form of a spiral, means for rotating said last mentioned elongated member, and means for effecting electric discharges between said two 110 elongated members. 115

10. A document protector comprising, in combination, a supporting surface having a longitudinally extending gap therein, a pair of relatively movable elongated conductors mounted to extend longitudinally of said surface in said gap and positioned one on either side of said supporting surface, said conductors having their adjacent portions in angular relationship to provide a spark gap therebetween at a single point, means for 120 125

130

- effecting electric discharges across said gap, and means for relatively moving said conductors to produce a change in position of said spark gap.
- 5 11. In a document protector, the combination of a pair of elongated current-conducting members mounted for relative movement in spaced relation to each other, said members having an angular relationship to provide a single adjacent point therebetween constituting a spark gap, and means for effecting relative movement between said members to produce a change in position of said spark gap.
- 10 12. In a document protector, the combination of an elongated conductor, a second conductor mounted in spaced relation to said first conductor, and means for moving one of said conductors relatively to the other, said conductors being constructed so that at least the adjacent portions thereof have an angular relationship whereby said relative movement effects a shifting of the position of the adjacent portions.
- 15 13. A document protector having, in combination, a pair of electrical conductors mounted in spaced relation to form a spark gap, and means for moving said conductors relatively to each other to vary the position of said spark gap.
- 20 14. In a document protector, the combination of a pair of electrical conductors mounted in spaced relation to form a spark gap through which a document may be passed, and means for relatively moving said conductors to effect a movement of said spark gap transversely of the direction of movement of the document.
- 25 15. In a device of the character described, the combination of means defining a guide for a document to be treated, a pair of electrical conductors mounted adjacent said guide and spaced apart to form a spark gap through which said document must pass, and means for producing a rapidly recurring movement of said spark gap transversely of said passageway.
- 30 16. A device of the class described having, in combination, a plurality of electrical conductors mounted in opposed spaced relation to provide a spark gap therebetween, a high potential circuit in which said conductors are included whereby to cause sparks to jump between the opposed conductors, the device being constructed to permit a sheet of paper to be drawn through the spark gap between said conductors, and means for effecting a movement of at least a portion of said conductors to effect a shifting of the sparks relative to the document during the passage of the document through the device.
- 35 17. A device of the character described having, in combination, electrical means providing a gap through which sparks are caused to jump, said means being constructed to permit a sheet of paper to be drawn through said gap, and means for causing movement of said electrical means to shift the position of the sparks relative to the paper during passage of the paper through the device.
- 40 18. A device of the class described having, in combination, a high potential electrical means providing a spark gap through which a sheet of paper may be drawn, and means for effecting rapidly recurrent transitory movements of the sparking area to form closely spaced minute perforations throughout a large area of the paper.
- 45 19. A device of the character described having, in combination, a plurality of electrical conductors mounted in opposed spaced relation to provide between them a spark gap through which a document may be passed, a high potential circuit in which said conductors are included whereby sparks will be caused to jump between the opposed conductors and through the document, and means for effecting a traverse of the sparks in a direction transverse to the direction of movement of the paper and thereby form minute perforations throughout a large area of the document.
- 50 20. In a device of the character described having, in combination, a plurality of electrical conductors mounted in opposed spaced relation to provide therebetween a spark gap through which a document may be passed, a high potential circuit including said conductors for producing the passage of sparks across said spark gap, and means for feeding a document through said spark gap.
- 55 21. In a device of the character described having, in combination, a plurality of electrical conductors mounted in opposed spaced relation to provide therebetween a spark gap through which a document may be passed, a high potential circuit in which said conductors are included for producing the passage of sparks across said spark gap, and switch means for controlling the flow of current through said high potential circuit.
- 60 22. In a device of the character described having, in combination, a plurality of electrical conductors mounted in opposed spaced relation to provide therebetween a spark gap through which a document may be passed, a high potential circuit in which said conductors are included for producing the passage of sparks across said spark gap, means for feeding a document through said spark gap, and a control switch for said high potential circuit connected to said feeding means for movement into circuit closing position during the feeding operation of said feeding means.
- 65 23. In a device of the character described having, in combination, electrical means providing a gap across which sparks are caused to jump and arranged to permit a document

to be drawn through said gap, a feeding means for drawing said document through said gap, a switch for controlling the passage of electric current through said electrical means, 5 means connecting said switch and said feeding means to move said switch into a circuit closing position while said feeding means is in operation, and means yieldingly resisting said circuit closing movement to effect an 10 automatic circuit interrupting movement thereof substantially at the moment said feeding means ceases to operate.

24. A method of treating written documents which comprises passing the document 15 through a spark gap provided between two opposed spaced electrical conductors and causing sparks to jump from one conductor to the other through the document to perforate both the written and unwritten areas of 20 the document.

In testimony whereof, I have hereunto affixed my signature.

IRVEN H. WILSEY.
